SCAVENGING TWO-CYCLE INTERNAL COMBUSTION ENGINE

Application filed February 23, 1928, Serial No. 256,310, and in Germany February 28, 1927.

Our invention relates to the scavenging of internal combustion engines. It is an object of our invention to provide scavenging means in which whirling movement is imparted to the gases and all residues of exhaust gas in the cylinder are practically removed.

To this end we provide scavenging ports or passages which are so proportioned and inclined tangentially and axially with respect to the cylinder that the entire cylinder space is swept uniformly by the scavenging air. A whirling motion results from this arrangement of the ports or passages because the helical movement of the air particles which prevails at the lower dead centre is, on the upward stroke of the piston, gradually deformed into a spiral and finally becomes circular. When this point is reached, fuel is injected, preferably by means of a plurality of separate jets at uniform angular pitch so that the fuel is uniformly distributed in the compression chamber.

In internal combustion engines having port scavenging the efficiency of the scavenging is a function of its thoroughness. It is desirable that no residues of exhaust gases should remain in the cylinder after scavenging. When the inlet and outlet ports for the scavenging air are at opposite ends of the cylinder, an efficient scavenging is readily attained, but when the inlet and outlet ports are arranged at the same end of the cylinder the problem becomes more difficult. Heretofore in engines of the latter type, the scavenging air flowed principally along the inner walls of the cylinder, leaving in the cylinder a core of exhaust gas which was not entrained by the scavenging air.

In order to overcome this drawback it has been suggested to conduct the scavenging air from the inlet ports toward the axis of the cylinder so that it was deflected toward the walls of the cylinder at the upper end of the cylinder and flowed down toward the outlet ports along the cylinder walls. The converse arrangement has also been proposed, but both these methods are not satisfactory as they still leave a hollow cylindrical space between the upward flow in the axis and the downward flow along the walls of the cylinder which

space is not permeated by the scavenging air. This drawback cannot be eliminated by causing mere whirling movement of the central flow.

It has also been attempted to generate a plurality of variously directed streams of scavenging air by suitably inclining the inlet ports on one side of the cylinder, the streams issuing from the several ports travelling through the cylinder in paths of different length before escaping from the outlet ports on the opposite side of the cylinder. With this method the central regions of the cylinder but not the regions at its walls are permeated by the scavenging air, so that this method is also imperfect.

These drawbacks are overcome, according to our invention, by so arranging the ports that the streams of scavenging air rise at an angle to the axis of the cylinder along a helical line, being first conducted toward the axis of the cylinder and then deflected toward the angles at the cylinder cover. The air flows in a loop and at the same time rotates through an angle of about 360 degrees around the axis of the cylinder so that the cylinder volume is thoroughly swept by the scavenging air. This can be concluded from the fact that the path of the air particles is much longer than in any other existing method, owing to the combined loop and helical movements.

In the drawings affixed to this specification and forming part thereof cylinders of two-cycle internal combustion engines embodying our invention are illustrated diagrammatically by way of example.

In the drawings

Fig. 1 is an axial section of a cylinder having the inlet and outlet ports for the scavenging air distributed over an angle of 180 degrees each on opposite sides of the cylinder,

Fig. 2 is a section on the line II-II in Fig. 1,

Fig. 3 is a section on the line A-B in Fig. 2,

Fig. 4 is a cross-section of a cylinder in which the inlet ports are arranged at a somewhat lower level than the outlet ports, and the two sets of ports are arranged in over-

lapping relation, Fig. 5 is a section on the line V—V in Fig. 4.

Referring to the drawings, *a* is a cylinder, *b* is its piston which is assumed to be at the 5 lower dead centre, *c* is the cylinder cover and *d* is the cylinder space. *E* is a header for supplying scavenging air, *e'* are inlet ports in the cylinder. *a* and *e* is a passage inclined at an angle to the axis of the cylinder and connecting the ports with the header. Fig. 2 10 shows that the inlet ports *e'* extend through an angle of substantially 180 degrees in plan.

The passage *e* to which the several ports *e'* are connected, is inclined upwardly at an 15 angle α with respect to the head of the piston and the ports *e'* are so arranged that the horizontal projections of their axes are tangents to a circle the diameter *d* of which is small as compared with the inside diameter of the 20 cylinder *a*. Figs. 2 and 5 illustrate the flow of a particle of air from one of the inlet ports *e'* to one of the exhaust ports *f'*. The particle leaves the port *e'* at 1, first moves in a straight line as far as the circle *d*, and then upwards 25 in a slightly curved line until it impinges against the cylinder wall at 2. At this point it is gradually deflected tangentially while rising to the point 3 below the cylinder top. While moving in this path the tangential 30 component imparted to the particle is still active and causes the particle to flow in a chord 3, 4 below the cylinder top whereupon it moves downwardly along the cylinder wall for some distance and finally is deflected into 35 the exhaust port *f'* on a substantially helical line 4, 5. In this manner each particle moves in a loop while at the same time rotating about the axis of the cylinder. Finally the 40 gas is discharged through the outlet ports *f'* which are connected with an inclined passage *f* as will appear from Fig. 1. The outlet ports also extend over an angle of about 180 degrees opposite the inlet ports *e'*, as shown in Fig. 2.

45 Obviously the scavenging ports or each set of them, that is the inlet and outlet ports, might extend over a larger or smaller part of the cylinder than corresponds to 180 degrees and the inlet or the exhaust ports, or 50 both, might be arranged otherwise than radially.

Referring now to Figs. 4 and 5, the arrangement of inlet and outlet ports *e'* and *f'* is the same, each set extending over an angle 55 of 180 degrees, but the sets are arranged at different levels and in overlapping relation which requires staggering of the passages *e* and *f*. The relative position of the sets corresponds to an angle of 270 degrees.

60 By arranging the ports at various levels and by staggering them it is obvious that a larger port area may be arranged for a cylinder of given diameter than with the ports at the same level as in this case the limiting 65 angle for either set is 180 degs.

We wish it to be understood that we are not limited to the particular case illustrated in Figs. 4 and 5 but that the sets may be overlapped as desired.

By our arrangement of ports the volume 70 of air and gas in the cylinder is rotated throughout the cylinder space without undue resistance. The rotary movement of the particles occurs along a helical line when the piston *b* is at its lower dead centre, as 75 shown, but the helix angle is reduced gradually while the piston is moving toward the upper dead centre. In the vicinity of the upper dead centre the curve is flattened out 80 into a spiral and finally the particles move along circular paths. This circular movement of the scavenging air, which now plays the rôle of combustion air, is very important for complete combustion and indispensable 85 for solid injection, and it will therefore be understood that our method of imparting the described movement to the scavenging air is also very important from the point of view of complete combustion.

Various changes may be made in the details disclosed in the foregoing specification without departing from the invention or sacrificing the advantages thereof.

We claim:—

1. A two-cycle internal combustion engine 95 having a cylinder, and scavenging and exhaust ports in said cylinder in the vicinity of its lower dead center position, the axes of said scavenging ports being arranged at an angle to the transverse axis of the cylinder such that the diameter of the circle to which the axes of the scavenging ports are tangent is small compared to the inside diameter of the cylinder, and said scavenging ports being inclined to the vertical axis of the cylinder 100 at an angle such that the scavenging air currents pass through the cylinder space upward at an angle in a direction located between the radial and tangential planes such that they strike the opposite cylinder wall above 105 its center and flow along the wall of the cylinder in a helical line up to the cylinder cover after which they cross the cylinder cover in the direction of a chord and then flow downward along the cylinder wall to 110 the exhaust ports.

2. A two-cycle internal combustion engine having a cylinder, and scavenging and exhaust ports in said cylinder in the vicinity of its lower dead center position, characterized by 115 the fact that the scavenging ports are arranged tangentially with respect to the transverse axis of the cylinder at an angle such that their axes are tangent to a circle of a diameter less than one-third the cylinder diameter and that they are inclined to the vertical axis of the cylinder at an angle such that the scavenging air passes through the cylinder in a loop which only once encircles the cylinder axis.

3. A two-cycle internal combustion engine having a cylinder, and scavenging and exhaust ports in said cylinder in the vicinity of its lower dead center position, said scavenging ports being inclined upwardly toward the head of the cylinder at an angle such that their center lines meet the opposite cylinder wall above the center of the region covered by the piston stroke and being at an angle with respect to the transverse axis of the cylinder such that their center lines are tangent to a circle less than one-third the diameter of the cylinder.

10 In testimony whereof we affix our signatures.
